By Philip L. King

ATTYS.

UNITED STATES PATENT OFFICE

HARRY V. BALL, OF CONCORD, MASSACHUSETTS, ASSIGNOR TO R. HOE & CO., INC., OF NEW YORK, N. Y., A CORPORATION OF NEW YORK

PRESS ARRANGEMENT

Application filed April 4, 1928. Serial No. 267,330.

This invention relates to certain improvements in multi-unit printing machines.

In large multi-unit printing presses, that is, printing presses in which there are a large number of printing units and appropriate folding mechanism, economy of space in the arrangement of the press mechanism in the press room is of great practical importance to the press user. It is desirable, further-
more, in this class of machines that the units be so arranged that they are on one floor level; and so that a clear space is provided around the units, so that the plate cylinders of the couples may be easily and rapidly plated from one plate conveyor.

It is the especial object of the present invention to provide an improved multi-unit press arrangement of large capacity in which the units may be arranged compactly so as to economize space in the press room, and an arrangement in which a clear space is provided around the printing units so there is clear access to the cylinders for plating or other purposes.

A further object of the invention is to provide such an arrangement in which each perfecting unit will include printing couples which will be preferably arranged in superposed relation in similar but separate framing, this framing being narrow, that is, of little more than the width necessary to accommodate the form and impression cylinders and the inking mechanism, and in which the inking mechanism is arranged within the framing and below the form cylinders of the couples.

A further object of the invention is to provide an arrangement in which web guides are provided for leading a web to and through the couples from below, and further web guides for leading a web above or over the units to a folder arranged on the same floor level as the units, so that the space around the units is free and clear without web interference.

A further object of the invention is to provide such an arrangement of units that where the couples of a unit are arranged in superposed relation the form cylinders of both couples may be supplied with plates from one conveyor, a platform being provided on which

the operator may stand when plating the cylinders of the upper couples.

With these and other objects not specifically referred to in view, the invention consists in certain novel parts, arrangements and combinations which will be described in connection with the accompanying drawings and the novel features pointed out in the claims hereunto annexed.

In these drawings, which illustrate a preferred embodiment of the invention,—

Figure 1 is a side elevation of the improved press arrangement, the parts being shown more or less diagrammatically; and

Figure 2 is an end view of one of the printing units illustrating the construction of the platforms and the position of the plate conveyor.

Referring now to these drawings, there are shown three printing units marked A, B, C and a folder indicated generally by the letter D. Each of these units includes a pair of printing couples which, in the particular construction illustrated, are mounted in superposed relation to each other. The units are identical and in the construction shown are mounted and arranged in the same manner, so that a description of one will suffice for all. In the particular construction illustrated, referring to unit A, there is provided a lower printing couple 1 including a form cylinder 2 and an impression cylinder 3, and an upper printing couple 4 including a form cylinder 6 and an impression cylinder 5, these two couples forming a perfecting unit.

While, if desired, these two couples 1, 4 may be mounted in a single frame, in a preferred construction and as shown these couples are mounted in separate similar frames. Whether the couples are mounted in separate frames or in one frame, this framing, as shown, will be narrow, that is, but slightly wider than the width necessary to support the form and impression cylinders, so that a greater number

of printing units may be arranged in a given space than may be done with prior known arrangements in presses of the multi-unit type. Furthermore, the units will all be on the same floor level, so that all the couples may be

plated from one plate conveyor hereinafter referred to.

The framing for supporting the couples, of course, may be varied widely in construction, but as shown each of the separate frames will include standards 7, 8 rising from a base 9, these standards supporting frames 10 in which the plate and impression cylinders find bearings. Where separate similar frames are provided in superposed relation, the web 10 of the lower frame may support the base 9 of the upper frame, and the frames 10 of the upper frame may form a support for superposed framing 11 in which are supported certain web guiding mechanisms hereinafter referred to.

It will be observed that the cylinders of each couple are arranged in transposed position relatively to each other, that is, the form cylinder 2 is arranged in the right hand side of its framing and the form cylinder 6 is arranged in the left hand side of its framing, the impression cylinders being similarly transposed.

In the particular construction shown, the plate and impression cylinders of each couple are horizontally aligned. It will be understood, however, that while this arrangement is preferable other arrangements of the cylinders of each couple relatively to each other may be made.

Inking mechanism is provided for the plate cylinders of each couple, which is preferably located below the couple and within the confines of the framing, considered vertically. Thus an inking mechanism 12 is provided for plate cylinder 2, and an inking mechanism 13 for plate cylinder 6. In the best constructions, the webs are run in from below, and web guides are provided for guiding the webs to and through the couples of each unit, and other guides for guiding the webs above the units to the folder, so that each unit has a clear accessible space on both sides, thus permitting ready access to the parts of the mechanism. As shown, the web W for unit A is led over guide rolls 14, 15 to and between the cylinders 2, 3 of couple 1 and then over guide rolls 16, 17 to and between the cylinders 5, 6 of couple 4. It will be observed that guide rolls 15, 17 are so located that a small wrap of the web on the impression cylinders is provided, which is desirable.

In the best constructions, the webs are guided from above the printing units so that there is no web interference. As shown, there are provided web guides 18, supported in the framing 11, before referred to, which guide the web above the units to the folder. The webs from all the units are similarly guided and may be associated at the folder.

In arrangements embodying the invention in its best form, platforms are provided arranged at a convenient height to enable the operator to reach the upper plate cylinders

and these platforms are so arranged with respect to a plate conveyor 19 that the pressman may take plates from the conveyor either from the floor level 20 or from the platforms. These platforms are indicated generally by numeral 21 and are hinged at 21' so that they can be moved out of the way when desired, and preferably are divided as shown in Figure 2, so that one part of the platform may be down to enable an operator to stand thereon to plate an upper form cylinder and the other half of the platform may be raised to permit a pressman to plate a lower form cylinder.

The units may be driven in any suitable manner, as by a line shaft 22 having gears 23 meshing with gears 24 on vertical shafts 25 which, through gearing 26, drive the couples.

Under some circumstances, if desired, where the couples are mounted in separate similar frames, the two couples may be arranged side by side in horizontal relation to form a perfecting unit, suitable web guides being provided for guiding the web through the units thus formed.

It will be apparent from the construction shown and described that a very compact multi-unit press of large capacity has been made in which the units are open and accessible from both sides, and in which the cylinders, where arranged superposed, may be plated with a single plate conveyor, indicated at 19, accessible to the pressman from the floor level or from the platform level.

Furthermore, by feeding from below and carrying the webs overhead to the folders arranged on the same level with the printing units, a larger number of units may be arranged in a smaller floor space than can be done with press arrangements heretofore used.

In the drawings three units and a folder are illustrated, but it will be understood that as many units and folders as desired may be used, and with the folders in any desired relation with the units or groups of units, the number and arrangement shown being only illustrative of the invention.

While the invention has been shown and described in its preferred form, it will be understood that various changes may be made in the specific construction shown and described and in the particular arrangement of the invention without departing from the invention as defined in the appended claims.

What I claim is:

1. In a multi-unit press arrangement, the combination of a plurality of printing units each including a rotary printing and perfecting couple arranged in superposed relation on one floor level, framing in which the couples are mounted and of a width not substantially greater than the width of each couple, the framing for the units being spaced apart so as to leave a clear space on each

side of each unit, inking mechanism for the couples arranged below and within the vertical planes of the couples, and web guides for leading the webs around the inking mechanism through the printing units with a substantial lap on each impression cylinder.

2. In a multi-unit press arrangement, the combination of a plurality of printing units each including a rotary printing and perfecting couple arranged in superposed relation on one floor level, narrow framing in which the couples are mounted, the framing for the units being spaced apart so as to leave a clear space on each side of each unit, inking mechanism for the couples arranged below the form member of each couple and within the outer vertical plane tangent to the outer periphery of the form member and extending into the space below the impression member of the couples, and web guides for leading the webs around the inking mechanism and through the units from a web supply below the press and with a substantial lap on each impression cylinder.

3. In a multi-unit press arrangement, the combination of a plurality of printing units each including a rotary printing and perfecting couple arranged in superposed relation on one floor level, the cylinders of the couples being arranged in vertical alignment, narrow framing in which the couples are mounted, the framing for the units being spaced apart so as to leave a clear space on each side of each unit, inking mechanism for the couples arranged within the vertical planes tangent to the outer peripheries of the form members of the couples, and web guides for leading the webs around the inking mechanism and through the printing units, with a substantial lap on each impression cylinder.

4. In a multi-unit press arrangement, the combination of a plurality of printing units each including a rotary printing and perfecting couple arranged in superposed relation on one floor level, narrow framing in which the couples are mounted, the framing for the units being spaced apart so as to leave a clear space on each side of each unit, inking mechanism for the couples arranged below and within the vertical planes tangent to the outer peripheries of the form members of the couples and extending into the space below the impression member of the couples, web guides for leading the webs around the inking mechanism and through the printing units from a web supply below the press, a folder, and web guides above the units for leading the webs to the folder.

5. In a multi-unit press arrangement, the combination of a plurality of printing units each including a rotary printing and perfecting couple arranged in superposed relation on one floor level, the cylinders of each couple being arranged in vertical alignment and

in the same horizontal plane, narrow framing in which the couples are mounted of a width not substantially greater than the width of each couple, the framing for the units being spaced apart so as to leave a clear space on each side of each unit, inking mechanism for the couples arranged within the vertical planes tangent to the outer peripheries of the form members of the couples, web guides for leading the webs around the inking mechanism and through the printing units from a web supply below the press, a folder, and web guides above the units for leading the webs from the printing mechanism to the folder.

In testimony whereof, I have hereunto set my hand.

HARRY V. BALL.
